CHAIR BACK

Warren D. Petersen, St. Charles, Ill., assignor to
Interlake, Inc.

Filed Oct. 27, 1972, Ser. No. 301,483

Term of patent 14 years

U.S. Cl. D6—197   Int. Cl. D6—06

FIG. 1 is a perspective view of the chair back of my design;

FIG. 2 is a front elevation view of the chair back of my design;

FIG. 3 is a cross sectioned elevation view as viewed substantially along line 3—3 of FIG. 2 of the chair back of my design showing the geometrical shape of the components of the chair back;

FIG. 4 is a top plan view of the chair back of my design as viewed substantially along line 3—3 of FIG. 2;

FIG. 5 is a bottom plan view of the chair back of my design as viewed substantially along line 5—5 of FIG. 2.

I claim:

The ornamental design for a chair back, as shown.
